ROCKING RAILWAY JOURNAL BOX

Per Gunnar Palmgren, Philadelphia, Pa., assignor to SKF Industries, Inc., Philadelphia, Pa., a corporation of Delaware

Application June 21, 1950, Serial No. 169,357

6 Claims. (Cl. 105—223)

This invention relates to a journal box for railway axles arranged to permit limited axial motion of the axle within a self-aligning bearing assembly.

A principal object is to provide a journal box capable of swinging laterally to accommodate the unavoidable weaving motion of the axle on the track.

Another object is to construct the journal box so that it may follow the weaving motion of the axle by rocking laterally on an outer curved supporting surface.

Another object is to limit the lateral rocking of the box substantially to the extent of the relative lateral motion between frame and axle.

Another object is to construct the rocking surface so that it creates a force tending to reverse its direction of swing, said force starting from zero and increasing in value as the box tilts farther from upright position.

Still another object is to construct the rocking surface so that the rocking movement is controlled either by steps or smooth rolling motion against increasing resistance.

A further object is to contour the intersecting surfaces of the box and frame so that the car load will produce couples tending to slow down swinging of the axle relatively to the frame.

In a preferred embodiment, the invention contemplates a railway axle journal box and side frame assembly wherein the axle is afforded the required limited axial float through freedom of the box to rock in the frame, the resulting angular displacement of the box with respect to the axle journal being accommodated through medium of a single self-aligning roller bearing for said journal suitably mounted in the box.

Fig. 1 shows in sectional elevation the railway journal box of this invention;

Fig. 1a is a sectional elevational view showing the box and bearing outer race tilted by movement of the axle to the left;

Fig. 2 is a view similar to Fig. 1 showing another and preferred embodiment of the invention;

Fig. 2a is a view similar to Fig. 1a illustrating the mode of operation of the embodiment shown in Fig. 2;

Fig. 3 shows a front elevational view of the box assembled in the side frame of a railway car;

Fig. 4 is an end view of the frame and box assembly as viewed from the line 4—4, Fig. 3;

Figs. 5, 6, 7 and 8 are fragmentary sectional elevational views illustrating modifications within the scope of the invention, and

Figs. 9 and 10 are diagrammatic views illustrating two different applications of the principles of the invention.

Because of the necessity for axial clearance between wheel flange and rail, and because of the conical shape of the wheel rim, there is always a tendency in rail cars for the axle to move back and forth axially when the car is in motion. In addition, the rail is never quite straight which also results in axial motion of the axle. In order to reduce communication of axle motion to the truck, and thence to the car body, journal bearings of the plain type are allowed clearance for axial float between thrust

2

surfaces of journal and of the brass of the bearings. This permits the journals to slide axially across the brass pillows to the limit of the total clearance before striking the thrust shoulders.

5 The present invention provides a journal box organization, including a self-aligning anti-friction bearing assembly, wherein the box is afforded freedom for angular displacement of sufficient magnitude to accommodate the axial weaving of the axles without communication of undue amounts of that axial motion to the trucks of the car body. In this organization the self-aligning bearing assembly functions to permit the relative angular movements between the box and the axle which must necessarily accompany the aforesaid angular displacements of the box.

In one embodiment, the invention consists of a journal box 1 provided with a truck frame supporting surface 2 at the top in the form of a segment of a cylinder struck from a horizontal axis through the center 3 of the bearing, normal to the axis of the journal, the said surface being curved therefore in the direction longitudinally of the axle. The box is also provided with lugs 5a and 5b integral with the box and arranged to limit its angular motion, and to support lateral loads, as its cylindrical surface rocks on a flat surface 6 in the side frame 7. The box contains a single self-aligning roller bearing 8 for the axle journal having an outer raceway surface 9 of spherical form also centering at 3. The box has a width considerably greater than that of the side frame 7, and the said lugs at the sides have a horizontal spread greater than the pedestal opening, as in Fig. 4 wherein the box is shown in the pedestal opening. Lugs 5a and 5b are spaced from the walls of the side frame by clearances 10a and 10b which correspond with the amount of rocking resulting when the axle moves axially from central to extreme left, or right, position with respect to the side frame. When the axle moves to the left, the inner face of lug 5a strikes the adjacent wall 11a of the side frame, while lug 5b strikes wall 11b when the axle moves right. Fig. 1 shows the box in central vertical position. It will be noted that in Fig. 1a the center 3 of the inner race of the bearing has moved with axle 12 horizontally to the left, as indicated by arrow A. The box and outer race have rocked through small angle d.

45 Fig. 1 shows the self-aligning roller bearing, at the left end of the axle, in its upright central position. The lugs 19a and 19b at the top of the box, spaced from the side walls of the frame by small clearances 20a and 20b serve to position the box close to the center while allowing the necessary swing. Since the axle would seldom lie perfectly perpendicular to the direction of the track, it will move transversely thereto as the car starts. Let us consider the axle to move to the left for the purpose of describing the action of the invention. Fig. 1a shows the axle as moving horizontally toward the left, carrying the bearing center 3 along the coincident axes of bearing and axle to point 3a. It also carries the inner race 13 and rollers 14 the same distance. Pressure of the load on the cylindrical top of the box prevents the latter from moving horizontally left but forces it to rock as illustrated. Freedom for this rocking movement, with its resultant angular displacement of the box with respect to the axle, is afforded by the self-aligning bearing which provides the necessary horizontal axis of oscillation for the axle journal in the box, said axis intersecting the bearing center 3 normal to the journal axis and paralleling or approximately paralleling the aforesaid axis of the rocking surface 2. Since axial motion of the axle occurs only when the train travels, the rollers will follow a helical path over the outer raceway up to the amount of tangential pressure across the contact surface 9 at which resistance to sliding breaks down so that sliding occurs.

In the embodiment in which the axis of the cylindrical rocking surface coincides with the center 3 of the spherical outer raceway of the bearing, the outer ring of the bearing and the box will rock as shown in Fig. 1a, moving the location of load support to the left from vertical plane 16, which contains the centers of bearing and of box when in their upright positions, to plane 17 which contains the center of the bearing in its shifted position. In this case the box rocks without raising the frame relatively to the horizontal centerline of the axle, encountering only the extremely low resistance of rolling friction, and limited by the striking of the lug 5a against wall 11a of the frame. Since the line of loading always passes vertically through the center 3 of the supporting bearing, the box remains stable in every rocked position. Forces created by the continual weaving motion among car bodies, frames, trucks and axles, due to conicity of wheel rims, unevenness of tracks, and play between members of truck frames, act to keep the box in oscillation within limits permitted by the lugs.

If the cylindrical truck frame supporting surface is struck from an axis which lies below the bearing center 3, say through the point 4 in Figs. 2 and 2a, so that the surface has a radius longer than the distance from bearing center to the said surface, rocking of the box as illustrated in Fig. 2a, will move the said axis of the cylindrical surface to 4a, which is a greater distance than it moves the bearing center. The plane of load application by the frame to the top of the box will thus have moved from location 16 to location 18 wherein the said plane passes through the shifted point 4a. The plane of load application, therefor, stands a distance g to the left of the support plane 17, so that a couple is created tending to reverse the direction of swing of the box, the couple having a value in pounds inches equal to the product of load times g . The device provides a box permitting limited lateral movements of the axle from a centralized upright position resisted initially by rolling friction, and in addition by forces tending to reverse the direction of swing, said forces increasing in intensity as the box tilts further from the upright position.

Obviously the supporting surface at the top of the box, could have forms of curves other than cylinders, symmetrical with respect to the central vertical plane, which could accomplish the above described results in modified degrees. For example, a surface whose radius of curvature increases as the surface progresses on either side of the plane of symmetry, as illustrated at 21 in Fig. 5, will throw the loading plane further and further beyond the supporting plane, as the box rocks further and further from the vertical position. In other words, the restoring force will increase at a higher rate than with a cylindrical surface. When the radius of curvature reaches infinity the surface becomes flat and the loading plane shifts instantly from the center of the flat to its edge. A flat surface, therefor, maintains the box in a definite position until the rocking couple overcomes the restoring couple, i. e., until force along the center line of the axle times its distance from the flat, overbalances the load times one-half the width of the flat.

Obviously also the tilting characteristic of the box may come in part from an antifriction bearing of the type having its inner instead of its outer race of spherical form, as shown in Fig. 6, wherein the inner race ring is indicated by the reference numeral 22 and the spherical race surface of this ring, the center of which corresponds to the center 23 of the bearing, by the reference numeral 24. The rollers 25, in this instance, have concave rolling surfaces conforming to the convex surfaces 24 of the inner race and 26, 26 of the outer race. The required tilting characteristics may be obtained also by the use of a bearing assembly which includes an adapter for the bearing, see Fig. 7, having a spherical surface 27 for contact with a matching spherical surface 28 within the box, the bearing 29 in this case being of conventional double row

tapered type. Any such spherical surface combined with a rocking surface in accordance with the principles set forth above will permit lateral motions of the axle and provide the same restoring forces at every location of the loading plane as in the above described embodiment, the value of those forces depending upon the ratio in that loading plane, of the radius of curvature of the rocking surface to the distance from the bearing center to the rocking surface.

- 10 The supporting surface may possess different forms at different symmetrical locations on either side of the central plane of the box, which give it an action characteristic of each location. A supporting surface composed of a series of flats each successively diverging toward the axle at a small angle from the preceding one, would regulate the tilting in steps, as distinguished from the smoother action provided by curves. A polygonal surface of this character is illustrated in Fig. 8 wherein as in the other figures the side frame is indicated by the reference numeral 7, and the individual flats of the rocking surface of the journal box by the reference numeral 30. The angle between the adjoining flats should not exceed that which would result in the box moving into an unstable position when shifting from one flat to another, i. e., the center of the bearing should never advance beyond the vertical plane through the edge of the flat about which the shift occurs. A combination of flats and curves, would provide degrees and types of control, as desired by the designer, at every location.
- 15 30 Each of the above embodiments exhibits a form of surface adapted for rolling or tilting with respect to the flat surface now conventionally provided on the side frame, and Figures 2, 5 and 7 illustrate organizations in which restoring couples come into play as soon as the box starts tilting from vertical position, and increase with continued tilting. The principle of the invention, however, as indicated above, may find other embodiments.

- 20 35 In one modification, Fig. 9, the frame surface 41, or if desired a supplementary surface attached thereto, is concave in form so as to embrace the convex seating surface 42 on the box. With this arrangement, and for any given angular displacement of the box, the axial displacement of the interseating or contact area between the surfaces will be not only greater than the axial displacement of the bearing center, but the ratio will be relatively high. Thus, a displacement of the bearing center 3, Fig. 9, from the vertical plane 43 to the point 3a, will be accompanied by an axial movement of the contact area from the plane 43 to the vertical plane 44. This affords a relatively quick and large restoring couple which may be indicated by the arrows 45 and 46.

- 25 40 In another modification, Fig. 10, the frame may present a convex seating surface 47 to a convex box surface 48. With this arrangement the contact area between the surfaces will have a lesser axial displacement than the accompanying displacement of the axle. Thus, a movement of the bearing center 3 from the vertical plane 49 to the vertical plane 52, will be accompanied by an axial movement of the contact area from the plane 49 to the plane 50. In this case, therefore, the restoring couple is absent, and a small upsetting couple, indicated by the arrows 53 and 54, is developed.

- 45 50 In general, the balanced condition illustrated in Fig. 1, or the restoring couples described above, are considered desirable, since they either avoid unstabilizing forces or actually produce forces tending to stabilize the axle in central position and the box in upright position. The embodiment of Fig. 10, which in effect tends to stabilize the axle in the positions of extreme axial displacement from the central position with the box tilted to one or other side of the upright, may be found useful under certain conditions of load and structure. It is evident, also, that the required rocking action may be obtained by provision of a flat frame-supporting surface on the box and a coacting convex seating surface on the frame.

Such arrangement, however, while falling within the broad principle of the invention, tends to increase the magnitude of the "up-setting" couple.

All the above discussion of supporting surfaces assumes their formation accurately to specification. Such accuracy may prove impractical in some cases especially when using cast iron parts. Wear or pounding may also alter original surfaces and thus change the rocking action originally designed. This invention extends to all such variations.

As described above, the invention contemplates a journal box having a frame-supporting surface offset from the center line of the axle and arranged for coaction with a suitably formed frame surface to permit limited rocking movements of the box in the frame, together with self-aligning means within the box affording freedom for the accompanying relative angular movements between the box and the axle. The forms of the interseating surfaces, their location, and the form and arrangement of the self-aligning means may vary widely without departure from the invention.

It will be understood that the term "rolling" as used in the appended claims is intended to embrace tilting and any other form of relative movement between the interseating surfaces of the frame and journal box which is substantially free from sliding friction.

I claim:

1. A journal box for the axles of rail cars, said box comprising a self-aligning bearing assembly for the axle journal affording freedom for relative oscillatory movement between the axle and the box about a horizontal axis intersecting the center of said bearing assembly and normal to the journal axis, said box having also a surface remote from and above said axis of oscillation convexly curved in the direction longitudinally of said axle and forming a seat for the side frame of a rail car truck on which the box may rock with respect to said frame in response to longitudinal displacement of the axle, said seating surface and bearing jointly affording freedom for said longitudinal displacements of the axle with respect to the frame, and the radius of the said curvature of the seating surface exceeding the distance of said surface radially from the said axis of oscillation.

2. A journal box according to claim 1 wherein the curved frame-seating surface defines an arc of a cylinder.

3. A journal box according to claim 1 wherein the radius of curvature of the frame-seating surface is variable and increases progressively on each side of a median position.

5 4. A journal box according to claim 1 wherein the curved frame-seating surface exhibits a polygonal profile in the vertical cross sections normal to said horizontal axis.

10 5. A journal box according to claim 1 wherein the convexly curved seat for the side frame supports a concave surface on the underside of said frame, the radius of the said seat being shorter than the radius of said concave surface.

15 6. In a rail car side frame and axle journal assembly, a journal box containing a self-aligning bearing for the journal comprising an inner race ring secured against axial displacement to the journal, an outer race ring secured against axial displacement in the box, and rolling elements confined between and securing said rings against relative axial displacement, said bearing affording freedom for oscillation of the box relative to the axle about a horizontal axis through the bearing center and normal to the journal axis, a side frame-seating surface on the box above said bearing center on which said frame is supported in vertical alignment with said center, said seat being convexly curved in the direction longitudinally of the axle so as to allow the box to rock on the frame in response to axial displacements of the axle with respect to the latter, and the radius of curvature of said seating surface exceeding the distance of the surface radially from said horizontal axis.
